UNITED STATES PATENT OFFICE

ARTHUR RICHTER, OF BERBISDORF I. E., GERMANY

FLAT HOSIERY FRAME

Application filed August 29, 1930. Serial No. 478,727.

The present invention relates to a flat hosiery frame in which the frame head or the sinker bars are moved upwardly and downwardly for the purpose of shortening the vertical movement of the needle bars. Such a machine is naturally very efficient since the rotational speed can be essentially increased due to the shortened vertical movement of the needle bars.

10 The machine is equipped with guide bars on which the known welt bars, hanging on the drawing off mechanism, slide which are hung therein for the purpose of drawing off the fabric from the first rows of loops of the 15 parts of the fabric. If these guide bars were rigidly connected with the machine, as heretofore, could not be prevented that, for example, when lowering the frame head particularly the sinkers would collide with the 20 welt bars when the welt bars still project in the sinkers which is the case when only one row of loops is to be produced. Also the needles of the needle bars may interfere with the welt bars and this is absolutely to be 25 avoided. For this purpose the guide bars, on which the welt bars slide, are movably connected with the machine so that they will participate in the vertical movement of the frame head and the sinker bars.

30 One embodiment of the invention is illustrated in the accompanying drawings, in which Figure 1 is a side view of the new device and Fig. 2, a plan thereof.

Referring to the drawings, the guide bars 35 1 are oscillatorily arranged around the bearings 3 secured to the support 2, and they are further movably attached to the sinker bars 4 or the frame head 5 in any suitable way. Therefore, if the head 5 moves with the 40 sinker bars 4 vertically in the direction of the arrow x (Fig. 1), the guide bars 1 will oscillate about the pivot 6 in the direction y , the welt bars participating in the vertical motion of the sinkers so that trouble of any kind 45 is avoided.

To adjust the small differences in length during the oscillation of the guide bars 1, they are disposed at one end in the slots 7. It will be found advantageous to place the 50 fulcrum 6 as closely as possible to the draw-

off mechanism 8 to prevent the rear end of the bar 1 from moving in a direction opposite to that of the front end.

The device described can be used also if the frame head reciprocates horizontally or 55 if a horizontal reciprocating and a vertical up and down motion are combined.

I claim:—

1. A flat hosiery frame comprising a plurality of sinker bars, and a plurality of guide 60 bars adapted to support a welt bar, said guide bar participating in the motion of the said sinker bars.

2. A flat hosiery frame according to claim 1 including a take-up, and a plurality of pivots, the plurality of guide bars being oscillatorily arranged relative to the said pivots at the ends facing the take-up. 65

3. A flat hosiery frame according to claim 1 in which the guide bars are movably connected with one end of the said sinker bars. 70

4. A flat hosiery frame according to claim 1 in which bearings are provided for the guide bars for permitting longitudinal motion of one end thereof. 75

5. A flat hosiery frame comprising a sinker bar, and a guide bar adapted to support a welt bar, said guide bar cooperating with the sinker bar to participate in the motion of the sinker bar. 80

In testimony whereof, I have signed my name to this specification at Dresden, Germany, this 21st day of August, 1930.

ARTHUR RICHTER.
